UNITED STATES PATENT OFFICE

THEODORE S. FULLER, OF MONTCLAIR, NEW JERSEY

DEVICE FOR DISPENSING PIPE CLEANERS

Application filed March 13, 1930. Serial No. 435,444.

This invention relates to devices for cutting pipe cleaners.

Among the objects of the present invention, it is aimed to provide an improved device for dispensing pipe cleaners, which consists of a casing for containing a roll of a flexible strand constituting the pipe cleaner material and a mechanism for discharging a desired length of pipe cleaner, and cutting off such discharged length.

These and other features, capabilities and advantages of the invention will appear from the subjoined detail description of one specific embodiment thereof illustrated in the accompanying drawings in which

Figure 1 is a perspective view of the improved device with a length of pipe cleaner extending therefrom.

Fig. 2 is a side elevation of the same with one of the casing walls removed.

Figure 3 is a section on the line 3—3 of Fig. 2 with the removed casing wall in place.

Fig. 4 is a section on the line 4—4 of Fig. 2 with the removed casing wall in place.

In this device there is provided a casing 1 having a plane rear wall 2 and a U-shaped lateral wall 3 and a plane upper wall 4. These walls 2, 3 and 4 may be composed of one piece as illustrated in the present instance as for instance, one formed out of bakelite. For this casing 1 in the present instance, there is provided a cover plate 5 similar in shape to the rear wall 2 and preferably secured to the casing 35 by a frictional metal flange piece 6 secured to the cover 5 and extending into the casing 1 when the cover is in place so that this frictional flange piece 6 will frictionally engage the inner face of the U-shaped lateral wall 3. This frictional flange piece 6, as clearly illustrated in Fig. 2, when the cover is in place, extends along a part of the inner surface of the upper wall 4 and then continues down along a greater part of the inner face of the U-shaped lateral wall 3.

Substantially centrally located of the rear wall 2 there is provided a stub shaft 7 upon which is mounted a reel 8 of usual construction on which is wound the pipe cleaner material 9 which, instead of being formed of a

plurality of predetermined lengths as customary today when marketing such pipe cleaners, consists of an elongated uncut length. This pipe cleaner material is of the usual type such as a flexible strand comprising a flexible wire support on which is secured an absorbent material such as cotton, or the like.

In the present instance the free end of the pipe cleaner material extends up past the discharging mechanism consisting essentially of a knurled wheel 10 loosely mounted on a shaft 11 which is journalled in the bracket 12 secured to the upper end of the casing 1 adjacent to the outlet 13 through which the pipe cleaner material 9 passes when being dispensed. The lateral wall 3 is provided with an opening 14 to permit a portion of the surface of the knurled wheel 10 to project therethrough to be engaged by the finger of the user.

For properly guiding the length of the material to the wheel 10 there is provided a shield 15 secured to the bracket 12 and having an opening 16 just large enough to permit the material 9 to freely pass therethrough and guide the same into engagement with the face of the knurled wheel located inside of the casing 1.

For forming an abutment for impinging the pipe cleaner material 9 by the knurled wheel 10 there is provided the block 17.

In the operation of this discharge mechanism the pressure of the finger of the user on the wheel 10 will frictionally impinge the material 9 against the shoe or block 17 so that when the wheel 10 is thereupon rolled or turned by the finger while still exercising such pressure, the material 9 will be effectively fed upward and outward through the opening 13. After the free end of the material 9 extends sufficiently from the casing 1 so that the user can grip same, he may wish to pull the material out instead of operating the wheel 10. In order to facilitate such pulling action and prevent the same being opposed by the wheel 10, there is provided a spring 18 extending upwardly from the lower end of the bracket 12 and resiliently pressing the wheel 10 outwardly so that it will sub-

stantially liberate the material 9 to permit it to be freely drawn from the casing 1.

After the desired length of material 9 has been discharged or fed out of the casing 1, before the same is ready for use as a pipe cleaner, it will be necessary to cut off such length. In the present instance, a shearing mechanism is provided consisting of the blade 19 pivotally connected at 20 to the upper end of the bracket 12 and having an arm extending away from the discharge opening 13 toward the opening 21 through which the finger piece 22 formed on the blade 19 extends.

In the present instance the bracket 12 is provided with an extension 23 extending along the lower face of the blade 19 and secured beyond the opening 21 to the rear wall of the casing 1. On this extension 23 there is formed a stud 24 on which is mounted the coiled end 25 of a spring arm 26, the free end of which extends over into engagement with the projection 27 extending downwardly from the blade 19. This spring arm 26 functions resiliently to maintain the blade 19 clear of the material 9 so that the finger piece 22 rests against the rear wall 2 as shown in Figs. 1, 3 and 4.

The blade 19 is provided with a shearing or cutting edge 28 as particularly illustrated in Fig. 3. This cutting edge 28 is inclined relative to the rear wall 2 in order to facilitate this shearing action when the blade 19 is moved forwardly toward the cover 5 in this shearing operation. Obviously, to operate this shearing mechanism, it is only necessary to press the finger piece 22 forwardly toward the cover 5 against the tension of the spring arm 26 when the shearing edge 28 will engage the material 9 to cut off the same just below the opening 13. Releasing the finger piece 22 the spring arm 26 will return the blade 19, where the finger piece will again rest against the rear wall 2.

The frictional securing means for the cover 5 consisting of the frictional flange 6 already described is provided to facilitate the removal of the cover 5 by the user so that he can without difficulty wind a new supply of material 9 on the reel 8.

It will also appear that the spring 18 acts as a check pawl to prevent reverse rotation of the wheel 10. If the wheel were not so protected, the strand 9 might be caused to feed back upon the reel 8 and require rethreading through the shield 20 and opening 21.

It will also appear from the foregoing that the cutting edge 28 of the blade 19 operates with the bracket 12 to affect the shearing action on the strand 9 when the blade 19 is actuated.

It is obvious that various changes and modifications may be made to the details of construction without departing from the gen-

eral spirit of the invention as set forth in the appended claims.

I claim:

1. In a pipe cleaner dispenser, the combination with a casing, of a reel mounted in said casing for supporting a strand of pipe cleaner material, there being an opening in said casing, an abutment disposed adjacent to said opening, a feeding wheel disposed opposite to said abutment to receive the free end of the pipe cleaner material and co-operating with said abutment to feed a length of said material through said opening when said feeding wheel is operated, a shearing blade pivotally mounted in said casing, said shearing blade having a knife edge disposed adjacent to said opening in position to engage and cut off the length of material discharged when said shearing blade is operated, and a spring for engaging said shearing blade normally to maintain it out of cutting position.

2. In a pipe cleaner dispenser, the combination with a casing, of a reel mounted in said casing for supporting a strand of pipe cleaner material, there being an opening in said casing, an abutment disposed adjacent to said opening, a feeding wheel disposed opposite to said abutment to receive the free end of the pipe cleaner material and co-operating with said abutment to feed a length of said material through said opening when said feeding wheel is operated, a shearing blade pivotally mounted in said casing, said shearing blade having a knife edge disposed adjacent to said opening in position to engage and cut off the length of material discharged when said shearing blade is operated, a spring for engaging said shearing blade normally to maintain it out of cutting position, and a second spring co-operating with said feeding wheel to permit the free withdrawal of said pipe cleaner material through said opening when said feeding wheel is not operated.
